UNITED STATES PATENT OFFICE.

WERTER O. GRAHAM, OF HATTIESBURG, MISSISSIPPI.

PLUMB RULE AND LEVEL.

988,705.

Specification of Letters Patent.

Patented Apr. 4, 1911.

Application filed August 29, 1910. Serial No. 579,522.

To all whom it may concern:

Be it known that I, WERTER O. GRAHAM, a citizen of the United States, residing at Hattiesburg, in the county of Forrest and 5 State of Mississippi, have invented a new and useful Plumb Rule and Level, of which the following is a specification.

My invention consists of a combined plumb and level and has for its principal object to 10 provide a simple and effective means for visually indicating the difference in level between a true horizontal plane and the plane undergoing test or measurement.

A further object of the invention is to 15 provide a device of this character in which the delicately balanced arbor will not be controlled by the usual gravitating poise or counter-weights depending therefrom.

A still further object is to provide a device 20 of this character which will register the most inappreciable deviations and will be provided with double dials and needles in order that these indications may be visible from either side of the level.

25 With the above and other objects in view which will appear as the nature of the invention is better understood, my invention embraces the structure illustrated in the accompanying drawings and set forth in the following specification, it being understood 30 that changes in the structure herein disclosed can be made within the scope of the claims without departing from the spirit of the invention.

35 In the accompanying drawings:—Figure 1 is a view in elevation of a combined plumb and level constructed in accordance with my invention showing the needle dial and case complete and set in the level. Fig. 2 is a 40 vertical section through the line A—B of Fig. 1 showing a needle arranged on each side of the dial. Fig. 3 is a view in elevation showing the reverse side of the combined plumb and level from Fig. 1. Fig. 4 is an 45 enlarged sectional detail of the needle arbor and its bearings. Fig. 5 is an enlarged fragmentary detail showing the manner in which the ends of the arbor are journaled in the jeweled bearings.

50 Referring to the drawing for a detailed description of my invention in which like characters of reference designate similar parts in the different views 1, indicates a level stock substantially rectangular in contour and cross section and having its upper

and lower plane edges formed into true planes. The level is preferably made of well seasoned wood or like material which will not warp or twist out of shape and may be ornamented if desired in order to give a 60 neat and finished appearance to the article. Formed at the intersection of the longitudinal and cross center lines of the level is a transverse annular opening 2 sufficient in size to receive and snugly fit the dial case. 65

The dial case is preferably formed of metal and comprises a substantially cylindrical shell 3, one end of which is provided with an outwardly extending flange 4 which is countersunk into the level, and at the 70 other end the case terminates flush with the surface of the reverse side of the level and is provided with external screw threads 5 to engage the counter-sunk metal ring 6. This ring is provided with internal screw threads 75 to engage the external screw threads of the dial case, and when in engagement therewith will securely bind the parts together and prevent any further movement of the same. Formed on the inner periphery of the dial 80 case 3 intermediate the ends is an annular mortise 7 designed to receive the dial plate 8. The dial plate or sector 8 is preferably in the form of a ring, both faces of which are graduated by indices that divide the 85 360° of arc into extremely small subdivisions in order that the minutest deflections of the needle may be indicated.

Mortised into the bore of the dial case on either side of the dial 8 are glass disks constituting observation plates 9 and 10 which form closures for the ends of the dial case and prevent dust and other foreign matter from gaining entrance to the delicate indicating mechanism contained therein, while 90 at the same time clearly exposing the indices on both of the lateral faces of the dial to view. In the center of each observation plate is formed a circular opening 11 in alignment with the axis of the case designed 95 to receive the bearing studs 12. Each of these studs projects through the alined openings 11 and terminates at one end in an enlarged head 13 and at the other in a screw threaded end 14 adapted to engage the internal screw threads of a tubular bearing 15.

Each of the tubular bearings 15 is provided with an internal circular beveled groove 16 formed adjacent one end and adapted to seat two jewels 17 and 18. The 110

jewels 18 are preferably plano convex, as shown, the convex side of the jewels bearing against the beveled sides of the grooves 16, as shown, so that a true adjustment of the 5 bearings may be obtained. The bearings 17 are concavo-convex and are provided at their centers with perforations in which the conical ends of the arbor 19 are journaled. In this manner the arbor is delicately swiveled 10 in proper position.

Positioned on the arbor 19 are a pair of needles or dial pointers 20 and 21 which are positioned on either side of the longitudinal center of the arbor and are so spaced apart 15 that they will operate on opposite sides of the dial. The lower ends of the pointers are preferably thickened, in order to cause the weight thereof to hold the pointers in true vertical positions at all times.

20 In order to permit the indicating mechanism to be inserted in the dial case, the case is made in two halves each of which are provided with alternate interfitting projections 22 and depressions 23, as shown. The case 25 may be further secured to the level by screws or similar connectors 24 if desired. For the purpose of permitting the shell 3 to be rotated slightly so as to permit it to be accurately adjusted the screws 24 are ex- 30 tended through arcuate slots 25 formed in the flange 4.

The device of the present invention is strong, simple, durable, and comparatively inexpensive in construction as well as thor-

oughly accurate, precise, practical and efficient in operation. 35

What is claimed as new is:—

1. A level comprising a stock, having an opening thereon, transparent plates in said opening, a pivoted pointer between said plates, said pointer having cone shaped fulcrumed points, jewel bearings secured to said plates, each of said bearings having a plano convex and a concavo-convex jewel therein, said concavo-convex jewel having an opening to receive the fulcrum of said pointer. 45

2. A level comprising a stock having a circular opening, a shell mounted in said opening and having an outwardly extending flange flush with one face of the stock, said flange having a plurality of arcuate slots, fastening members extending through said slots, a ring detachably secured to the side of the shell opposite said flange, a pair of transparent cover plates in said shell, an arbor journaled on said plates, a pair of spaced pointers fixed on said arbor, and a circular sector secured to said shell between 50 said pointers. 60

In testimony that I claim the foregoing as my own, I have hereto affixed my signature in the presence of two witnesses.

WERTER O. GRAHAM.
